UNITED STATES PATENT OFFICE.

GUSTAVE BURKHARDT, OF CHICAGO, ILLINOIS.

BOWLING-ALLEY LAMP.

Application filed November 20, 1922. Serial No. 601,999.

To all whom it may concern:

Be it known that I, GUSTAVE BURKHARDT, a citizen of the United States, residing at Chicago, in the county of Cook and State of Illinois, have invented certain new and useful Improvements in a Bowling-Alley Lamp, of which the following is a specification.

This invention relates particularly to a lamp for illuminating the pins in a bowling alley and for providing a lamp adjacent the pins to indicate that a foul has been made upon that alley. The principal object of the invention is therefore to produce a lamp of this kind, and a further object is to indicate clearly to the pin setter when a foul has been made so that he can reset the pins. A further object of the invention is to provide means for illuminating the pin setting area without shining into the eyes of the pin setter; another object is to provide a lamp of this kind in which the lamp holding sockets are freely removable from the reflectors, and in general, to produce a lamp of the class herein shown and described.

In the accompanying drawings, Fig. 1 represents a lamp of this kind as applied to the end of a bowling alley; Fig. 2 is a sectional view of the lamp proper; Fig. 3 is a face view of one of the reflectors; Fig. 4 is a view of another face when not illuminated; Fig. 5 illustrates the same face when illuminated; Fig. 6 shows a semi-circular indicator which may be included with the face shown in Fig. 4; and Fig. 7 illustrates a detail of the lamp holding construction.

In a bowling alley it is desirable that the pins be illuminated so that a bowler at the other end of the alley can see them clearly. If this light is left unguarded, it is hard on the eyes of the pin boy, and the present invention is intended to provide means not only for permitting the pin setting area to be sufficiently illuminated, but also to protect the eyes of the pin setter. In bowling tournaments it is customary to have an umpire watching the foul lines of a number of alleys, and it is desirable to have some clear indicating means for designating any alley upon which a foul has been made. For this purpose a lamp is provided which extends positively from the pin illuminating lamp but having a common support, by means of which the umpire can visibly indicate and designate the alley upon which a foul has been made.

Referring now more particularly to the drawings, a series of pins 1 are shown at the rear of an alley 2 with the present invention disposed slightly in advance and above the front pin. This fixture comprises a tubular member 3 having a depending supporting pipe 4. Extending from one end of the tubular member 3 is a reflector 5, and at the other end is an angular extension 6 for supporting a reflector 7. Extending from the top of this reflector 7 is a hood or guard 8 embracing substantially a semi-circle at the edges but having a central rounded depending tip 9 which extends over the center of the reflector and deflects certain of the light rays so that they will not shine into the eyes of the pin setter. This reflector 7 is inclined downwardly by the angular extension 6 so that the light rays therefrom will shine directly upon the pins 1.

In the rear of the reflector 5 is a bull's-eye 10 usually on one side or the other of the vertical center where it can be seen by the pin setter, and at the front of this reflector 80 there is usually a glass 11 with a character 12 on the lower half thereof indicating the number of the alley. This character is painted or otherwise applied to the glass 11 so that it will be visible whether the lamp 85 within the reflector 5 is lighted or not. At the back of the glass 11 and preferably extending over about half thereof is a partially transparent or opaque member 13 upon which designating characters 14 or the word 90 "Foul" appears in such a manner that when a lamp 15 within the reflector 5 is lighted, the designation "Foul" will be clearly apparent from the other end of the alley. In practice, the entire outer glass 11 is coated 95 or made partially opaque so that the partition 13 and the word "Foul" is not seen except when the lamp 15 is lighted but the character 12 is visible at all times. When the lamp 15 is lighted, the word "Foul" 100 clearly appears from the face of the reflector so that both it and the number of the alley is clearly visible from the other end of the alley, as indicated by Fig. 5. The main tubular portion and the angular extensions 105 6 provide receptacles within the reflectors 5 and 7 for removable lamp holders. The lamps 15 and 15' are each mounted in a plug or receptacle 16 at the back of which the current carrying wires are connected. The plug 16 may be seated directly in the tubular portions 3 and 6, but it is preferable to first

secure each of them in a short shell 17, and to secure the plug 16 in the shell by means of holding rings 18 attached to the shell. One of the shells 17 is provided with a cut 5 out portion 19 to extend around the edges of a fastening nut 20 by means of which the supporting tube 4 is attached to the member 3.

In electrically connecting the lamps of 10 this fixture there is a common conductor 21 connected to both of them, and a conductor 22 connected to one of them and a corresponding conductor 23 connected to the other one. Space is provided between the 15 plugs for loops 24 in the conductors by means of which the lamps and plugs can be withdrawn with their shells 17 from the tubular members and without disengaging the electrical conductors.

20 With this construction it is obvious that this fixture will operate both to illuminate the pin setting area but not to shine in the eyes of a pin setter, and to indicate the number of the alley and the alley upon which a 25 foul has been made. The lamps are easily removable for adjustment and repair.

I claim:

1. In a bowling alley lamp, a fixture support having a forwardly extending tubular portion parallel with the alley and a rearwardly and downwardly inclined tubular extension adapted to be disposed directly above and in front of the head pin position, illuminating means in the tubular portions, 35 that in the inclined portion being adapted to illuminate the pins, and means extending in front of the other tubular portion bearing a designation of the alley visible from the other end of an alley to which it is applied.
2. In a bowling alley lamp, a tubular member with an angular rear extension, means for supporting the member in a horizontal position with the extension inclined downwardly, and reflectors attachable one 45 in the front end of the member and the other in the extension, one reflector directing the light to cover the pin positions and the other being visible from the opposite end of an alley to which it is applied.
3. In a bowling alley lamp, structurally connected but oppositely extending reflectors and lamps, one inclined downwardly in advance of but toward the head pin position, and the other located at the front having means for designating the alley when its lamp is not lighted, and additional means bearing a different designation visible only when the front lamp is lighted.
4. In a bowling alley lamp, a reflector, a 60 transparent glass with an indicating char-

acter normally visible at the front thereof to designate the alley, a lamp in the reflector, means behind said glass and normally invisible but visible when illuminated by the lamp to indicate that a foul has been made, and means controllable at will from a distance for lighting the lamp to visibly designate to a player at the other end of an alley that a foul has been made upon that alley.

5. In a bowling alley lamp, a tubular supporting member, a reflector at each end thereof, a lamp for each reflector, plugs in which the lamps are mounted and shells in which the plugs are mounted, the shells being insertable within the ends of the tubular 75 supporting member.

6. In a bowling alley lamp, a tubular supporting member, one portion of which is inclined, a supporting pipe attachable through the said supporting member, and lamp supporting means insertable in the opposite ends of the tubular member, said means comprising insertable shells one of which is cut out to partially embrace the connected end of the supporting pipe, one lamp illuminating the pin positions and the other bearing a designation visible from the opposite end of an alley to which it is applied.

7. In a bowling alley lamp, a reflector, a 90 transparent glass with an indicating character at the front thereof, a lamp in the reflector, means behind said glass and normally invisible but illuminated by the lamp to indicate that a foul has been made, and a bull's-eye at the back of the lamp visible to 95 a pin setter to indicate that a foul has been called and designated by the lamp.

8. A bowling lamp comprising an inclined part mounted directly above and in advance of the head pin position to illuminate the 100 pins, and a forwardly projecting part with means indicating the number of the alleys and visible from the other end of the alley, and means within this forwardly projecting part and visible only when it is illuminated 105 to indicate a foul has been called.

9. In a bowling alley lamp, a reflector, a transparent glass with a normally visible indicating character at the front thereof, a lamp in the reflector, means behind said 110 glass and normally invisible but illuminated by the lamp to indicate that a foul has been made, a lamp at the rear to illuminate the pin positions, means for protecting a pin setter from the glare of the rear lamp, and a bull's-eye at the back of the front lamp visible to a pin setter to indicate that a foul has been called and designated by the lamp.

GUSTAVE BURKHARDT.
